MIXING DEVICE

Hermann Sohn, Dusseldorf, Germany

Application November 14, 1955, Serial No. 546,681

4 Claims. (Cl. 259—85)

This invention relates to a rapid mixing device consisting of a rotatable mixing drum and one or a plurality of mixing tools or the like arranged within the mixing drum.

In known devices of this kind the mixing tools are arranged eccentrically with respect to one or a plurality of main-shafts of the mixing drum and usually consist of rods, flat bars, plates, shovels, or baskets formed from wires arranged at a suitable distance from the shaft of the mixing tool.

Although machines of this known kind are usually thought to work satisfactorily, there frequently is the drawback that devices of this type are suited only for certain purposes, for example the mixing of coloring matter, artificial materials or the like, but can be used for other purposes, for example the compressing, granulating, polishing and clipping of surfaces, etc. of one or a plurality of materials only at a considerable loss of time.

The invention has for its object to devise a mixing machine by means of which also different kinds of working operations can be performed, such as the mixing and shaking up of materials, the trituration of coloring matter or the like, or the compressing or granulation of substances or mixtures. At the same time the mixing device is so constructed that the time or energy required for the performance of certain working operations can be reduced.

Another object of the invention is to achieve with the device an improved distribution or trituration than has been possible hitherto by means of known devices, so that vastly improved products as well as novel types of products can be obtained.

According to the invention the mixing device is provided with a rotating drum mentioned in such a way that its largest diameter is considerably larger than that of the mixing tool, but at least twice as large as the latter, whereby the shortest distance from the periphery of the mixing tool to the inner surface of the mixing drum is equal to or smaller than the square root of the largest diameter of the drum.

According to another feature of the invention the mixing device is so constructed that the shortest distance from the periphery of the mixing tool to the inner surface of the mixing drum is adjustable within the limits from 0 to the aforementioned maximum measure, whereby the adjustment may preferably be effected through an eccentric rotational displacement of the bearings of the shaft of the mixing tool.

The first mentioned feature of the invention produces the result that momentarily only a small quantity of the material enclosed in the mixing device is subjected to the mixing treatment, while the bulk of the material is located in non-operative position. This renders it possible (as was accidentally found out) that the mixing tool arranged in a mixing drum of a capacity of between 20 to 20,000 liters can be driven at a maximum circumferential speed of, for example 120 m./s.

2

Owing to the feature that temporarily only a small portion of the material is subjected to the treatment by the mixing tool, the torque of the shaft of the mixing tool is small, while the high speed of the mixing tool, in combination with the likewise rotating mixing drum, results in the feature that the total quantity is subjected to a more intensive treatment in a shorter time than has been possible hitherto.

Depending upon the nature of the material to be mixed and upon the purpose for which it is to be used, particularly when a triturating effect is to be produced, it is necessary to reduce the width of the gap (distance) between the periphery of the mixing or stirring tools and the inner surface of the mixing drum. The width of the gap will then preferably be between 1 to 0.2 mm.

The alteration of the width of the gap will then simultaneously result in an alteration of the angle of engagement, wherein by the angle of engagement is to be understood the angle formed between the tangent drawn at the point of shortest distance of the drum from the mixing tool and the tangent extending from the same point to the periphery of that mixing tool.

This angle is of particular importance for the flow of the material to be treated into the gap formed between the drum and the mixing tool and in whose (the gap) immediate proximity the material is subjected to the highest effect of the mixing tool or mixing tools.

According to the invention the mixing tools are so devised and arranged within the drum that they can easily be exchanged either through removal of a flange, or through separation into several parts and be replaced by other types of tools. An elastic packing ring serves as a means to close up the mixing tool toward the outside in air-proof and dust-proof fashion, whereby a valve or filter serves as a means to regulate the internal pressure with respect to the outside pressure. For gases, liquids and pastes the packing means are of the known type.

The easy exchangeability is important if the mixing device is to be used for several purposes, for example the shaking up and mixing, compression and granulation. For certain purposes and materials specific tools or combinations of tools are employed, whereby through reversal of the direction of rotation of the mixing tool or tools or of the drum the function of the tool or tools is changed.

The mixing drum is rotatable in a manner known per se and rotates about an axis which, in dependence upon the dimensions of the device, does not coincide with the axis of rotation of the mixing tool, whereby according to the invention the speed of rotation of the mixing drum and of the mixing tool are both absolutely as well as relatively with respect to each other regulatable, reversible and independent of each other.

Because of these possibilities the device is suited for many different purposes. It is for instance possible to successively carry out several working operations, for example the polishing of the original material, first, at low rotational speed and, then, at increasing rotational speed of the mixing tool; through admixture of other substances admixed if required at timed intervals; to compress through reversal of the direction of rotation; or to change the material physically or chemically through thermic treatment of the material. For this purpose the inner surface of the drum may be coated with a chemically neutral substance. Moreover, for the construction of the mixing tool and the other elements such materials may be employed which are indifferent to the substances to be treated, or which produce a catalytic effect upon the substances to be treated.

The invention further contemplates to feed or insert into the interior of the drum via a hollow journal of the latter spraying means or aerating means, or other means.

These means may be of different types and have in each case for their object the treatment of the material and/or the control of the mixing process.

Additional features and advantages of the invention will be understood from a consideration of the following detailed description taken in connection with the accompanying drawings, forming a part of this specification and in which several embodiments of the invention have been shown by way of example. However, I wish to say that the invention is not confined to any strict conformity with the showing of the drawings, but may be changed or modified, so long as such changes or modifications mark no material departure from the salient features of the invention as expressed in the appended claims.

In the drawings:

Fig. 1 is a front-view of the mixing device;

Fig. 2 is a front-view of a modified form of construction of the mixing device provided with a double jacket;

Fig. 3 is a diagrammatic illustration of the mixing drum and mixing tools;

Fig. 4 is a longitudinal sectional view of one of the journals of the mixing device as well as of the bearing for the journal, and of the means for feeding cooling and heating means via the journal into the drum and for discharging them from the drum;

Fig. 5 is a fractional view, partly in section, of the mixing tool and of the bearing means for the latter;

Fig. 6 is a view of a modified form of construction of the mixing tool;

Fig. 7 is a view of another modified form of construction of the mixing tool in which the effect produced by the tool is changed through reversal of its direction of rotation;

Fig. 8 is a view of still another modified form of construction of the mixing tool operating with a plurality of different mixing and treating means;

Figs. 9 and 9a are a side-view and fractional front-view, respectively, of a mixing tool consisting of two halves;

Fig. 10 is a view of a mixing tool having a plurality of stirring plates or pins tangentially secured to a shaft.

Referring now to the drawings in detail, the reference numeral 1 in the form of construction of Fig. 1 designates the mixing drum having the mixing tool 2 rotatably supported in the flanges 3. The shaft 4 carrying the mixing tool is provided with packing means 5 and carries on one side of the drum a driving pulley 6 driven in this embodiment from a loose V-belt sleeve 7 loosely mounted on the journal 8. The journal 8 is rigidly secured to the wall 9 of the mixing drum 1 and rotatably supported in a bearing 11 mounted on a support 10. Fastened on or at the support 10 is a motor 12, whereby the V-belt pulley 14 of the motor 12 drives the sleeve 7 and consequently also the mixing tool 2.

In addition to the journal 8 the mixing drum 1 is provided with a journal 16 rigidly secured to the side-wall 15 of the drum and rotatably supported in a bearing 17 mounted on a support 18 on the right side of the device. On the side of the bearing 17 extending away from the mixing drum 1 the journal 16 is provided with a coupling 19 connecting the journal 16 with a gearing, for example a worm gear 20 driven from a motor 21.

A counter weight 23 for the mixing tool 2, as well as a valve 23' for the regulation of a desired internal pressure, for example a partial vacuum, or a pressure above atmospheric, or for the leveling of the internal pressure with respect to the external pressure, are provided at the side-walls 9 and 15 of the drum 1, although these means may be arranged also at other suitable places.

In the modified form of construction illustrated in Fig. 2 the mixing tool 2 as well as the mixing drum 1 are driven only from one side of the device, while from the other side of the machine the heating or cooling means are admitted into the drum. For this purpose the device

is provided with double walls, i.e. the inner walls 9, 15 and the outer walls 24, 25.

The rotatable journal 26 is at one end rigidly secured to the drum 1. On the journal 26 is loosely mounted the sleeve 7 which is driven in the same way as already described for the form of construction of Fig. 1. The rotation of the drum is effected via the journal 26, whereby in this case the gearing 19 to 22 is fastened on or at the support 10 on the left side of the device.

In this form of construction the mixing tool 2 is regulatable and adjustable regarding its direction as well as speed of rotation by means of the gearing 13, while the drum is regulatable and adjustable by means of the gearing 22.

In a special form of construction the drum 1 is provided with a filling funnel 1a shown in Fig. 2 merely in dotted lines.

The feeding of the cooling means into the drum and the discharge of the cooling means from the drum is effected in the embodiment of Fig. 2 via the journal 27 (see Fig. 4) which at 28 is supported on the support 18 in a slide bearing 29. The journal 27 is provided with a bore 30 which is closed up at the end facing the wall of the drum by a plate 31. A central pipe 32 axially positioned in the bore 30 extends at 33 at a right angle through a radial bore 34 in the journal 27 and the flange 35. A bore 36 radially extending with respect to the bore 34 but offset from the latter receives a branch pipe 37 which is tightly secured in the journal 27 through screw connection. It will be seen, therefore, that both of the pipes 32 and 37 rotate together with the journal 27.

Fastened on the support 18 beside the bearing 28 is a supporting member 38 which projects beyond the end 39 of the journal 27. Provided in the hollow annular chamber of the supporting member 38 surrounding the end of the journal 27 are packing means 41 which with the aid of a sleeve 42 and screws 43 are secured in packing position. The sleeve 42 is further provided with a passage 40 through which projects the end of the central pipe 32 which at 44 is likewise surrounded by packing means 45 adapted for tightening by means of a ring 46. Secured to the ring 46 in a feed pipe 47, and to the sleeve 42 a discharge pipe 48 for the cooling and heating means, which are at rest when the journal 35, 27 is rotating.

Important for the mixing device is the way in which the mixing tools are arranged within the mixing drum. In Fig. 3 the reference character *d* designates the diameter of the mixing tool or the like, while *D* denotes the inner width of the mixing drum. According to the invention the ratio of the diameter *D* of the drum to the diameter *d* of the mixing tool is at least 2:1, whereby the shortest distance *h* from the circumference of the mixing tool to the inner wall of the drum should not be longer than $\sqrt{D}$. Denoted by *e* is the radius of the eccentric circle having its center located in the axis of rotation of the drum. *K'* and *K''* are two mixing tools of differently sized diameters. The tangents from the point of shortest distance from the drum to the mixing tool, extending from the inner surface of the drum and touching the peripheries of the differently sized mixing tools, form with the horizontal line the angles α' and α'' . It will be seen from the drawing that, with the distance *h* remaining the same, the angle α' increases in size when the diameter *d* decreases. The same is the case when the diameter *d* remains unchanged and when the distance *h* increases.

The angle α' is of special importance for the engagement capacity of the material to be mixed, and for that reason must not decrease for a certain material below a specific value, as otherwise the possibility exists that the engagement of the material will either be seriously reduced or completely annulled.

In the same way there exists a best value for the angle of engagement for a specific material.

It is possible, for example, to maintain, when the distance h decreases, the same angle of engagement, when the diameter d of the mixing tool likewise decreases, or vice versa.

The drum 1 rotates in the illustration of Fig. 3 about an axis extending through P, so that the material to be mixed is subjected in the area of the mixer to a relative speed u , which amounts to

$$u = \frac{\pi}{60} (dn_1 \pm 2en_2) [\text{m./s.}]$$

whereby n_1 designates the number of revolutions of the mixing tool, while n_2 designates the number of rotations of the drum. The plus and minus signs have to be regarded as signs of the direction of revolutions. In case of large numbers of revolutions of the mixing tool the relative speed is of secondary importance. The rotation of the drum is chiefly intended to produce a large whirling action in the material. The number of revolutions of the drum may be adapted to special conditions, whereby the accelerations caused by the peripheral speed are usually not bigger than the accelerations caused by the force of gravity.

According to what has heretofore been explained there result for a mixer as disclosed in the present invention, departing from a diameter $D=800$ mm. for the mixing drum, the following peak values:

$$d = \frac{1}{2}D = 400 \text{ mm.}$$

$$h = \sqrt{D} = 28.3 \text{ mm.}$$

$$\alpha' = \text{arc tang } \frac{\sqrt{h^2 + 2hr}}{r} = 0.55 \sim 29^\circ$$

Furthermore, if the peripheral speed of the mixing tool is 10 m./s. and the number of revolutions of the drum 12 r.p.m., there result

$$n_1 = \frac{60u}{d \cdot 3.14} = 480 \text{ r.p.m.}$$

$$n_2 = 12 \text{ r.p.m.}$$

$$e = \frac{D}{2} - h = 0.372 \text{ m. and, therefore, for the relative speed}$$

$$u = \frac{\pi}{60} (dn_1 \mp 2en_2) = \begin{cases} \sim 9.6 \text{ m./s., for rotation in the same direction} \\ \sim 10.5 \text{ m./s., for rotation in opposite direction} \end{cases}$$

Within the limits given in the example the influence of the relative speed, therefore, amounts to 10%.

The mixing tool is particularly devised for the mixing and trituration of various types of pulverized materials, and for that reason provided with bar-shaped or flat mixing members. Figs. 5 and 6 show a mixing tool consisting of a shaft 49 having mounted thereon at least two supporting members, for example plates 50. Arranged between and supported by the two plates 50 are a plurality of bars 51, which in the embodiment shown in the drawings are of circular cross-section, and which for special purposes rotatably support roller-like members 52.

It is further possible to employ instead of the plates 50 radially extending pins 50 adapted to carry the bars 51. The plates or pins 50 are directly fastened to the sleeve 53 which may be secured in its position on the shaft 49 by means of a wedge against displacement in axial direction. The sleeve 53 is provided with a collar 54 adapted to bear against packing means 55, whereby the necessary compressive pressure is exerted by a sleeve 58 shiftably positioned in the flange 56 and acted on by a spring 57. A nose 59 provided on the sleeve 58 is guided in a groove 61 provided in the flange-collar 60, safeguarding in this way the sleeve 58 against rotational displacement. The sleeve 58 is surrounded by packing means 62 arranged in an annular recess of the flange-collar 60. The pressure exerted by the spring 57 is adjustable by means of a tension ring 64. The shaft 49 has both of its ends (only one end having been shown in

the drawings) supported in a self-aligning roller bearing 65 accommodated in a cap 66, whereby the cap 66 is secured to the flange 56 in known manner by means of screws 67. By means of an annular collar 69 provided with packing means 68 the shaft 49 is tightly closed up, so that the lubricating grease introduced via the bore 70 cannot run out.

On one of the ends of the shaft, for example at 71, is fastened by means of a wedge 72 and a plate 73 a driving pulley 6.

As shown particularly in Fig. 5 the shaft 49 is eccentrically supported with respect to the flange-collar 74 of the flange 56, whereby the radial distance from the central axis of the shaft to the flange-collar is m or n , respectively. This makes it possible to adjust, through rotation of the flange 56, the distance h within the limits of the eccentricity $n-m$.

According to Fig. 6 the mixing tool may be provided with a plurality of roller-like members 52 which are rotatably supported on supporting bars 51. The roller-like members 52 are then provided at their ends with bearings 55 preventing the material to be mixed from entering into the enlarged inner space of the roller-like members 52. Through proper selection of the diameter d_1 of the roller-like members 52 it is possible to adapt the gap or distance h (see Fig. 3) to requirements. The construction is then devised in such manner that an easy exchange of the roller-like members 52 for various purposes of use is thereby enabled.

According to Fig. 7 the mixing tool—which in this case changes its function through reversal of its direction of rotation—consists of wings or plates 75 and 78 having their free ends curved in a possible direction of rotation and which may be radially secured to the shaft 49.

If the mixing tool of Fig. 7 rotates in the direction indicated by the arrow 79 the tool will whirl up the material and shake it up. If, on the other hand, the tool rotates in the direction of the arrow 80, then a friction effect or grinding effect is produced between the bottom 81 and the material to be mixed.

According to the embodiment illustrated in Fig. 8 the mixing tool consists of a plurality of different groups of tools, i.e. the groups 83, 84 and 85, whereby the groups 83 and 85 consist each of a knife-carrying shaft 86 and of a perforated plate 87, while the tool 74 consists of a pair of turning shovels.

In Figs. 9 and 9a the tool consists of two halves 90 and 91, whereby the two halves are secured to each other by means of screws 92 traversing projecting portions of the lateral plates 90 and 91. Tightening of the screws 92 causes the walls of the opening 93 to rest snugly against the shaft 49. The walls of the opening 93 may be provided with means (for example key-ways 94 and wedges) securing the tool in non-shiftable position on the shaft.

In Fig. 10 the tool consists of two plates 95 tangentially secured to the shaft 49. It is understood that instead of the two plates also a larger number of plates may be employed.

However, the invention is not confined to the use of mixing tool as hereinbefore described. It is also possible to employ other types of tools, for example stirring or agitating tools, fork-shaped prongs, plates of screw-like formation, and other tools adapted for the adjustment of its diameter with respect to the distance h .

In the embodiment shown in Fig. 2 the journal 26 is provided with a hollow inner passage. This passage is chiefly intended for the introduction therethrough into the interior of the drum of a shovel-like tool 96 fastened at the end of a rod for the purpose of taking out of the drum, while the latter is in operation, samples of the material in the process of treatment. But the passage may also be used as a means for the aeration of or for the removal of the air from the drum, or for the feeding or insertion into the drum or into the space between

the inner and outer walls of the drum of a means, for example an electric wire for the generation of heat, or any suitable kind of measuring means 100, or a material to be admixed, a liquid, a chemical reagent or the like. The invention also provides the mixing device within the mixing chamber with stationary or movable scraping means for the material. Furthermore, the mixing device is provided at all important places with measuring tools, indicating the temperature and the internal pressure within the mixing drum, within its jacket or at other places.

What I claim as new and desire to secure by Letters Patent of the United States is:

1. A rapid mixing device for the homogeneous mixing and trituration of various types of pulverized materials, comprising a rotary mixing drum provided for its rotation with a pair of journals rigidly secured to and axially extending from opposite side-walls of said drum; a pair of supporting members oppositely positioned on the sides of said drum and provided with bearings adapted for the rotatable support therein of the free ends of said journals; rotary mixing means positioned within said drum and supported in the side-walls of the drum eccentrically to the axis of the drum; regulatable driving means for said drum coupled to one of said pair of journals and adapted to rotate said drum according to requirements; and additional regulatable driving means for said mixing means likewise coupled to one of said pair of journals and adapted to rotate said rotary mixing means at high speed independently of the rotation of said drum, said driving means of said drum and said additional driving means of said mixing means being adapted for the adjustment of the direction of rotation as well as for the adjustment of the absolute speed and relative speed of said rotary drum and of said rotary mixing means.

2. A rapid mixing device for the homogeneous mixing and trituration of various types of pulverized materials, comprising a rotary mixing drum provided for its rotation with a pair of journals rigidly secured to and axially extending from opposite side-walls of said drum; a pair of supporting members oppositely positioned on the sides of the drum and provided with bearings adapted for the rotatable support therein of the free ends of said journals; rotary mixing means positioned within said drum and

supported in the side-walls of the drum eccentrically to the axis of the drum, said rotary mixing means being provided with adjustable supporting means adapted for the adjustment without alteration of the diameter of the mixing means of a suitable distance of the periphery of said mixing means from the inner surface of the drum, regulatable driving means for said drum coupled to one of said pair of journals and adapted to rotate said drum according to requirements; and additional regulatable driving means for said mixing means likewise coupled to one of said pair of journals and adapted to rotate said rotating mixing means at high speed independently of the rotation of said drum, said driving means of said drum and said additional driving means of said mixing means being adapted for the adjustment of the direction of rotation as well as for the adjustment of the absolute speed and relative speed of said rotary drum and of said rotary mixing means.

3. A rapid mixing device as specified in claim 2, in which the adjustment of the angle formed between the tangent extending from the point of shortest distance of the inner surface of the drum from the periphery of the mixing means to the periphery of the mixing means, and the horizontal line is effected through rotation of said eccentric supporting means of the mixing means.

4. A rapid mixing device as specified in claim 2, in which said mixing means consist of a rotatable shaft and of a plurality of rectangular plates having one of their long sides tangentially secured to said shaft.
